DESIGN FOR A FURNACE HOT WATER SECTION

Abram C. Mott, Jr., Lansdale, Pa.

Application May 4, 1933. Serial No. 48,011

Term of patent 14 years

To all whom it may concern:

Be it known that I, ABRAM C. MOTT, JUNIOR, a citizen of the United States, and a resident of Lansdale, Pennsylvania, have invented a new, original, and ornamental Design for a Furnace Hot Water Section, of which the following is a specification, reference being had to the accompanying drawing forming part thereof, in which:—

Figure 1 is a side elevation illustrating my new design for a furnace hot water section; Fig. 2 is a plan view, and Fig. 3 is a perspective view looking down from the top, and on a reduced scale.

I claim:—

The ornamental design for a furnace hot water section, substantially as shown and described.

ABRAM C. MOTT, JR.
